(57) **CLAIM**

The ornamental design for a sanitizer dispenser, as shown and described.

DESCRIPTION

FIG. 1 is a perspective view of a sanitizer dispenser showing our new design;

FIG. 2 is a perspective view of the sanitizer dispenser shown in an extended position;

FIG. 3 is a left-side elevational view thereof;

FIG. 4 is a top plan view thereof;

FIG. 5 is a rear elevational view thereof;

FIG. 6 is a right-side elevational view thereof;

FIG. 7 is a bottom plan view thereof;

FIG. 8 is a perspective view thereof, illustrated with the dispenser nozzle in an extended position;

FIG. 9 is a front elevational view thereof;

FIG. 10 is a left-side elevational view thereof;

FIG. 11 is a top plan view thereof;

FIG. 12 is a rear elevational view thereof;

FIG. 13 is a right-side elevational view thereof; and,

FIG. 14 is a bottom plan view thereof.

The broken lines shown in the drawing disclosure are for illustrative purposes only and form no part of the claimed design.
